UNITED STATES PATENT OFFICE.

PAUL CHARPENTIER, OF PARIS, FRANCE, ASSIGNOR TO FORGES & ATELIERS DE CONSTRUCTIONS ELECTRIQUES DE JEUMONT, OF PARIS, FRANCE, A FRENCH SOCIÉTÉ ANONYME.

OIL-BREAK ELECTRIC SWITCH.

Application filed May 25, 1925. Serial No. 32,762.

This invention relates to oil-break electric switches and the like.

The invention consists of an oil-break electric switch, cut-out or like apparatus particularly intended for producing the release of the gases produced by the rupture-arc and their escape into an expansion chamber, from the first moments of the formation of the said arc, and specially designed with a view to ensuring the energetic cooling of these gases, and to avoiding any rise of pressure and therefore any explosion in the said expansion chamber.

The improved apparatus comprises in particular a cylindrical body, made of insulating material and filled with oil, communicating with a passage likewise containing oil, in which the rupture-arc is produced between one or more stationary contact members and one or more movable contact members of any suitable shape; this passage opens into the expansion chamber, in which the gases generated by the arc can expand without restriction.

The invention also comprises the addition of various accessory features such as an arrangement for direct release at maximum load, shock resistances, and resistances for heating the oil.

Upon the annexed drawing, to which reference is made in the following description, the same letters indicate the same elements or parts.

Figure 1 represents diagrammatically the arrangement of the oil-break system.

Figure 2 is a sectional elevation of a switch constructed in conformity with the invention.

Figure 3 represents diagrammatically a modification hereafter described.

The rod or tube E, Figure 1, carries the movable contact member C and is adapted to travel vertically under the action of an operating mechanism, not represented in the drawing, in a body N, preferably of cylindrical shape, having walls of insulating material and filled with oil. An opening formed in the cover N₁ of the body N serves as guide for the rod E.

Upon the lower edge of the body N, there is fitted a sort of funnel L, through the opening in which there passes the movable contact member C intended to work in con-

junction with the stationary contact D, which extends almost up to this orifice, being fixed to the bottom of the expansion chamber K located beneath the body N.

The stationary contact D is surrounded by a pipe or passage M, which flares out at its top in the form of an inverted truncated cone around the funnel L, up to a level higher than that of the lower edges of the said funnel, the top of the pipe being in communication with the expansion chamber K. The latter chamber is hermetically closed, but may be provided with escape valves opening to the exterior.

When the body N of the apparatus is filled with oil, this oil passes into the pipe M through the orifice in the funnel L, until the pressure of the gases contained in the chamber K balances that due to the difference of the levels of oil in the body N and in the pipe M; this latter may communicate with a reservoir, likewise filled with oil, as will be explained hereafter.

The pressure of the gases contained in the chamber K is such that the stationary contact D is only covered by a shallow depth of oil.

Upon the breaking of the electric circuit controlled by the switch or cut-out apparatus, the movable contact C rises from the fixed contact D under the action of the operating mechanism, an arc being produced between these contacts; the gases evolved find a passage through the shallow layer of oil covering the contact D and are able immediately to expand into the chamber K, in which there may be arranged baffles, finely divided masses or gauzes made of metal, or any other suitable device for cooling these gases.

Moreover, the said vessel K can be filled beforehand with inert gases, such as carbon dioxide, nitrogen and the like.

Figure 2 shows the application of the oil-break system, represented in Figure 1, to an oil-break switch, but it is to be understood that the system can likewise be utilized for any other oil-break apparatus, whether automatic or not, such as circuit breakers, voltage or current limiters, lightning arresters and the like.

A tube A, Figure 2, constitutes the main movable contact, its lower end engaging in

the closed position between the fingers B on the main stationary contact, which is of any suitable shape.

10 An auxiliary break contact is afforded by a movable block C fixed to the lower end of a rod E, which slides in the interior of the tubes A, and by a stationary block D arranged between the fingers B; electrical connection between the members A and E is effected by brushes F fitted between them.

15 At the moment of release, the tube A, urged upwards by the mechanism operating the apparatus, escapes from the fingers B; during this movement the rod E is held fast by a pawl H which is introduced by means of a suitable device into a longitudinal slot A₁ formed in the tube A, the pawl H then pressing upon the collar E₁ integral with the rod E.

20 This slot A₁ is of such length that after a given stroke of the tube A, the lower edge I of the slot comes to bear upon the pawl H, which thereupon pivots around its fulcrum H₁ and frees the rod E.

25 A spring G, fitted around the rod E between the block C and the collar E₁, and compressed as long as the rod E is held fast by the pawl H, expands and suddenly forces the said rod E upwards as soon as the collar E₁ is freed; the final break of the circuit then takes place between the contact members C and D.

30 An arc being thus produced between the extremities of these contact members, the gases generated drive away the small quantity of oil covering the contact D, bend around the orifice in the funnel L, escape into the space included between the said funnel L and the bore of the passage M, and then penetrate into the expansion chamber K in which they cool off, passing for example through iron turnings or filings before expanding. The pressure of the gases contained in the chamber K is greater than the atmospheric pressure; it corresponds to that of a column of oil several decimetres high, depending upon the height of the insulating body N, which is governed by the working voltage of the apparatus; the said pressure might vary for example from one hundredth to one tenth of an atmosphere, according to circumstances.

35 It will be understood that the initial pressure of the gases from the arc can be only very slightly greater than the pressure of the gases existing in the chamber K, since the gases produced can expand into this chamber as soon as they are formed.

40 By reason of the upward movement of the contact member C, the arc formed between the members C and D is drawn out, but it is not surrounded by any sheath of gas. In fact there is no compression of the oil in the body N because the gases can expand freely into the chamber K.

An adjustable non-return valve O can be provided upon the walls of the chamber K in order to allow of varying at will the maximum pressure of the gases contained in the said chamber, and to ensure the escape into the free air of the gases evolved by the arc when they are compressed beyond the said pressure.

45 A series of baffles such as P and Q can be arranged in the chamber K in such a way as to cause the gases to circulate therein so as to increase the cooling effect.

50 A regulating valve such as O might also be used to allow of the reduction in size or partial suppression of the chamber K; in such a case it would only be necessary to provide the pipe M with a bottom cover and to connect its flaring or bell-mouthed top to the wall J of the chamber K; the capacity of the latter would then be reduced to the space R, this being designed to suit the requirements and the said space being placed in communication with the outer air through the medium of the regulating valve.

55 It will obviously be necessary to provide against the ignition of the gases escaping to the exterior from the valve O, which however will cause no difficulty.

60 In order to prevent any ignition in the interior of the chamber K, and to obviate possible explosion, there may be introduced into this chamber as already mentioned carbon dioxide or any other suitable inert gas, supplied through a pipe such as T, as represented in Figure 2, after the filling with oil.

65 The apparatus may be completed by a shock resistance; for this purpose there may be arranged in the body N, suitable contacts such as brushes U mounted in an insulating manner upon a support V of any suitable shape and adapted to press upon the tube A; the shock resistance may be formed by coils X connected between the contact brushes U and the funnel L or in any other manner.

70 The switch or cut-out apparatus constructed in accordance with the invention, may be provided moreover with an arrangement for release at maximum load by direct action, this being located in the metal cap Y surrounding the body N.

75 The conductors of the electric circuit controlled by the apparatus extend respectively one to the stationary contact members B and D by a suitable connection, and the other to an insulator Z fixed upon the cap Y of the body M. A lead a branching off at this insulator, enters the said cap Y by an insulating pipe b, then forms a winding c surrounding laminated cores d d₁ and is finally connected electrically by brushes f with the rod A.

80 The cores d d₁ which are of horseshoe shape, are arranged in such a way that their extremities face one another and are separated by an air-gap. The said cores

are carried by supports pivoted at $e e_1$ upon the cap Y , in such a way that they tend to come together under the magnetizing action of the current in the winding c , thereby compressing a device g in the shape of an articulated parallelogram. When the current passing through the winding c reaches a predetermined value, the sides of this device g are then sufficiently close together to cause the required movement of a rod h , which through known means produces the tripping of the automatic release mechanism.

The apparatus may also be fitted with a heating resistance j for keeping the enclosed oil at a suitable temperature; in this case the apparatus may comprise a hollow base k forming a reservoir in communication with the pipe M , the said resistance j being arranged in the interior of the reservoir at the position considered preferable in order to obtain a satisfactory circulation of the oil.

It has been mentioned above that the stationary contact D is surrounded by a pipe M ; it is evident that this pipe M can be suppressed if the expansion chamber K is given a shape such that its bottom end K_1 (see Figure 3 of the drawings) is at a higher level than the lower edges L_1 of the funnel L , and if its central part is made like a truncated conical basin S , filled with oil, the stationary contact D being secured therein.

What I claim is:—

1. An oil-break electric switch, comprising stationary and movable contacts, a basin surrounding said stationary contact, a funnel mounted above said basin, the lower opening of said funnel being within said basin, said movable contact guided to pass through said opening into engagement with said stationary contact, an oil-container surrounding said movable contact, said funnel forming the bottom end of said oil-container, and an expansion chamber in communication with said basin.

2. An oil-break electric switch, comprising a cylindrical oil-containing body, insulating walls to said body, a funnel forming the bottom end of said body, a top cover to said body, a movable contact slideable through said top cover, said contact adapted to pass through the lower opening in said funnel, a basin mounted beneath said funnel, the upper edge of said basin being at a higher level than said opening, a stationary contact arranged within said basin in line with said opening and with said movable contact, and an expansion chamber in communication with said basin.

3. An oil-break electric switch, comprising an oil container, a conical bottom end to said container said bottom end having an opening at its lowest part, a bell-mouthed cup beneath said bottom end, the edges of said cup being at a higher level than the

lower edges of said bottom end, a stationary contact fixed inside said cup, a movable contact within said oil-container, said movable contact adapted to pass through the opening in said bottom end into engagement with said stationary contact, and an expansion chamber in communication with said cup.

4. An oil-break electric switch, comprising an oil-container, stationary and movable contacts, said movable contact passing down through said container to engage said stationary contact, a funnel-shaped bottom end to said container, said end having an opening for said movable contact, an oil-containing basin surrounding said stationary contact, said basin having a flaring top extending above the level of the lower edge of said funnel-shaped end, and an expansion chamber in communication with the top of said basin.

5. An oil-break electric switch, comprising two oil-containing vessels, the upper of said vessels having a conical bottom end, the lower of said vessels having an open flaring top, said bottom end extending within said open top, a movable contact adapted to pass down within said upper vessel and through an opening in its bottom end, a stationary contact within said lower vessel in line with said movable contact, and an expansion chamber in communication with the open top of said lower vessel.

6. An oil-break electric switch, comprising an oil-container, a funnel forming the bottom end of said container, a contact movable through the opening in said funnel, a stationary contact beneath said funnel and in line with said movable contact, an oil-containing basin surrounding said stationary contact, the upper edge of said basin extending above the opening in said funnel, and an expansion chamber in communication with the interior of said basin.

7. An oil-break electric switch, comprising an oil-container, a funnel forming the bottom end of said container, a contact movable through the opening in said funnel, a stationary contact beneath said funnel and in line with said movable contact, an oil-containing basin surrounding said stationary contact, the upper edge of said basin extending above the opening in said funnel, an expansion chamber in communication with the interior of said basin, and an adjustable escape valve in said expansion chamber, said escape valve opening outwards for the release of the gaseous pressure.

8. An oil-break electric switch, comprising an oil-container, a funnel forming the bottom end of said container, a contact movable through the opening in said funnel, a stationary contact beneath said funnel and in line with said movable contact, an oil-containing basin surrounding said stationary contact, the upper edge of said basin ex-

- tending above the opening in said funnel, an expansion chamber in communication with the interior of said basin, and baffles within said expansion chamber, said baffles exerting
5 a cooling effect upon the gases.
9. An oil-break electric switch, comprising an oil-container, a funnel forming the bottom end of said container, a contact movable through the opening in said funnel, a
10 stationary contact beneath said funnel and in line with said movable contact, an oil-containing basin surrounding said stationary contact, the upper edge of said basin extending above the opening in said funnel,
15 an auxiliary contact supported by said movable contact, a spring controlling said auxiliary contact, a retaining pawl for said auxiliary contact, said movable contact adapted to release said pawl after a given stroke, and
20 an expansion chamber in communication with the interior of said basin.
10. An oil-break electric switch, comprising an oil-container, a funnel forming the bottom end of said container, a contact movable through the opening in said funnel, a stationary contact beneath said funnel and in line with said movable contact, an oil-containing basin surrounding said stationary contact, the upper edge of said basin ex-
25 tending above the opening in said funnel, an expansion chamber in communication with the interior of said basin, and shock resistance coils connected between said funnel and
30 said movable contact.
- 35 11. An oil-break electric switch, comprising an oil-container, a funnel forming the bottom end of said container, a contact mov-

able through the opening in said funnel, a stationary contact beneath said funnel and in line with said movable contact, an oil-
40 containing basin surrounding said stationary contact, the upper edge of said basin extending above the opening in said funnel, a base piece, an oil-reservoir in said base piece, said reservoir in communication with said
45 basin, an oil-heating resistance in said reservoir, and an expansion chamber in communication with the interior of said basin.

12. An oil-break electric switch, comprising an oil-container, a funnel forming the bottom end of said container, a contact movable through the opening in said funnel, a stationary contact beneath said funnel and in line with said movable contact, an oil-con-
50 taining basin surrounding said stationary contact, the upper edge of said basin extending above the opening in said funnel, a cap-
55 piece mounted upon said oil-container, said cap-piece insulated from said funnel, elec-
60 tromagnetic cores pivotally mounted within said cap-piece, means for energizing said cores by the current controlled by the switch, a trip rod for the automatic release of the switch operating mechanism, an articulated parallelogram arranged within said cap-
65 piece, said cores adapted to press upon opposite sides of said parallelogram, said parallelogram adapted to actuate said trip rod, and an expansion chamber in communica-
70 tion with the interior of said basin.

In testimony whereof I hereunto affix my signature.

PAUL CHARPENTIER.
